UNITED STATES PATENT OFFICE.

CHARLES H. ROBINSON, OF DEADWOOD, SOUTH DAKOTA.

GUARD FOR SMOKING-PIPES.

1,082,445.

Specification of Letters Patent. Patented Dec. 23, 1913.

Application filed June 12, 1912. Serial No. 703,258.

To all whom it may concern:

Be it known that I, CHARLES H. ROBINSON, a citizen of the United States, residing at Deadwood, in the county of Lawrence and 5 State of South Dakota, have invented new and useful Improvements in Guards for Smoking-Pipes, of which the following is a specification.

This invention relates to guards for smoking pipes, cigar holders or the like and has for an object to provide a foraminous member which is adapted to be inserted in the bottom of the bowl of a tobacco pipe and disposed at a point immediately in advance 10 of the smoke duct of the pipe so as to prevent the clogging of the latter by small particles of tobacco, and further the construction of a guard wherein the central portion thereof will consist of relatively close convolutions which are located directly above the 15 draft opening of the bore and designed to prevent the small particles of tobacco from being drawn into the bore, and outer convolutions which are spaced relatively so as to 20 permit of the required draft.

In the drawing forming a portion of this application, and in which like letters of reference indicate similar parts in the several views:—Figure 1 is a perspective view 25 of the guard. Fig. 2 is a section through the guard and through the bowl of a pipe showing the application of the former to the latter. Fig. 3 is a section through the guard, showing the same on an enlarged scale.

The device is constructed from a single 30 length of wire which is bent to provide an inner spiral or convolute horizontally disposed portion 1 whose convolutions 2 are spaced relatively whereby said guard is 35 rendered substantially foraminous to permit of a perfect draft of the pipe. The outermost convolution 2 of the portion 1 is extended into a substantially annular sustaining or supporting portion 3 having its free 40 terminal bent upwardly to lie against the inner wall of the bowl of the pipe 4 herein shown and provided with a hook 5 which is 45 adapted to embrace the upper edge of the bowl.

The portion 1 of the guard is disposed 50 adjacent to the bottom of the bowl of the pipe and immediately in advance of the duct 6 in the stem 7, being designed to support the tobacco in such manner that it will be held against being drawn into the duct 6 55 when draft is applied to the stem, thereby preventing the choking of the duct as will be understood.

The device is such that the portion 1 may be slightly expanded if desired whereby it 60 will readily accommodate itself to the inner diameter of the bowl. It is stated that the inner convolutions 2 of the portion 1 are disposed in closer relation than the outer convolutions whereby to give the article the 65 maximum effectiveness immediately above the duct 6 and to prevent small particles of tobacco from escaping through the guard at the center thereof. It is also said that the device as illustrated herein will positively 70 prevent the accumulation of tobacco in the extreme bottom of the bowl which lends admirably toward preventing the clogging of the smoke duct.

I claim:—

As a new article of manufacture, a guard 75 for smoking pipes, comprising a single length of wire having a charge supporting portion provided with many convolutions extending into each other and arranged so 80 that the inner convolutions are arranged in mutual contact relatively and the outer convolutions spaced relatively, the outermost convolution having a vertical supporting extension adapted to lie against the inner wall 85 of the bowl of the pipe and having means for connecting with the bowl so as to hold the charge supporting portion in operative position.

In testimony whereof I affix my signature 90 in presence of two witnesses.

CHARLES H. ROBINSON.
